GRATE

Charles V. Carroll, Minneapolis, Minn., assignor to Wm. Bros. Boiler & Manufacturing Co., Minneapolis, Minn., a corporation of Minnesota

Application August 7, 1944, Serial No. 548,398

9 Claims. (Cl. 126—163)

1

This invention relates to the design of grate surfaces used for supporting and/or furnishing air to a solid fuel bed for combustion on the grate surface, the grate surface design being applicable to any type of grate structure such as a shaker grate, dumping grate, chain grate or rotating grate. It is known that for efficient combustion of solid fuels without an undue excess air loss it is necessary to supply air uniformly to the under side of the solid fuel bed. This function of uniform air-supply has been accomplished in the past, with only partial success. It is an object of this invention to provide a more satisfactory design of grate surface capable of delivering air uniformly to the under side of a solid fuel bed. I have found that for efficient combustion of thin solid fuel beds particularly, it is desirable to supply the air in a manner so as to produce a swirling action and divergent air flow so that the solid fuel bed is provided with combustion air uniformly throughout its entire area.

It is an object of the invention to provide a grate surface of improved design capable of accomplishing these functions and yet of a design such that grate elements may be replaced easily without disturbing other elements. It is a further object of the invention to provide an exceedingly rugged grate element capable of withstanding rough usage and extreme temperature variations. It is a further and especial object of the invention to provide an improved grate surface capable of delivering air flow uniformly in a plurality of divergent swirling paths to a solid fuel bed without at the same time presenting any straight-through vertical passages over the grate area, and to provide a grate surface wherein the combustion air supply is metered through orifices and then expanded so as to reduce the air velocity and thereby reduce fly-ash difficulties. It is also an object of the invention to provide a grate surface of non-sifting character. It is a further object of the invention to provide an improved design of grate surfaces capable of being manufactured at low cost without the necessity of coring or other expensive molding procedures.

Other and further objects of the invention are those inherent in the apparatus herein illustrated, described and claimed.

The invention is illustrated with reference to the drawing wherein

Figure 1 is a top plan view of a single grate element;

Figure 2 is a side elevational view of a grate element illustrated in Figure 1;

2

Figure 3 is a top plan view of a grate element and a portion of two adjacent grate elements, one on each side;

Figure 4 is an enlarged fragmentary sectional view taken along the lines 4—4 of Figure 2;

Figure 5 is an enlarged fragmentary isometric view of a grate element of Figure 1; and

Figure 6 is a fragmentary sectional view of adjacent portions of two grate elements.

The grate surface of the present invention is illustrated as applied to a shaker or dumping type of grate but it will be understood to be applicable to other types of grates. Referring to the drawing there is illustrated a grate bar generally designated 10 of the type used in hand or stoker fired, stationary or movable boilers wherein the grate bars are mounting upon a carrier bar generally designated 11 which is trunnioned about pivots 12 so as to allow the carrier bar 11 and the grate bar 10 thereon to be rotated in the direction of arrow 13 for grate shaking and dumping operation. The fire surface of the grate bar 10, to the design of which the invention is particularly directed, is illustrated generally at 15 and may be considered as consisting of a thickened head portion having a top surface 16 and side surfaces 18 and 19, the side surfaces being parallel with each other and vertical. Along the upper corner formed at the junction of the top surface 16 and the side surface 19 there are provided a plurality of notches 20 of identical configuration and along the junction of the top 16 and side surface 18, there are a plurality of notches 21, likewise identical with those at 20. The notches 20 on the side surface 19 are staggered with relation to the notches 21 on the side surface 18, as shown in the drawing. The intervening spaces between the notches 20 and 21 are chamfered off slightly, as illustrated at 22 and 23, though the chamfering is not so extensive as to reach the level of the notches 20 and 21. The intervening spaces between the notches 20 and 21 are approximately equal in width to the width of the notches and each intervening space is provided with an air chute intaglio recess 24 formed into the side wall. Thus, as shown in Figure 5, the side wall 19 is provided with air chutes 24 having parallel walls 24a and 24b and a uniform intaglio depth illustrated by the bracket 24c.

The air chutes 24 terminate at the level of line 25—25, illustrated by the dimension A of Figures 2 and 5, it being noted that the air chute is tapered out as illustrated at 24e so as to cause the air moving upwardly in the air chute to be forced out

in the direction of the side wall 19. The notches 20 and 21 terminate at the level of line 28-28, Figure 2, which is lower than the line 25-25, as illustrated by the dimension B. The notches 20 and 21 are of gradually increasing width from bottom to top, as illustrated by the dimension C at the bottom of the notch, and the dimension D at the top of the notch, Figure 2. The walls 20a and 20b of the notches 20 and the corresponding walls 21a and 21b of the notches 21 are preferably not quite vertical and are filleted into the surfaces 20c and 21c of their corresponding notches.

Referring to Figure 1, it will be observed that the notches 20 terminate at a line 30-30 separated by the dimension E from the center line of the grate bar, the notches 21 being similarly terminated at the line 31-31, likewise separated from the center line by the dimension F. Dimensions E and F are preferably equal.

Referring to Figure 3 the grate bar 10 is mounted with its side surfaces in contact with the side surfaces of grate bars 10' and 10''. Thus the surface 18 of grate bar 10 is in contact with the surface 19' of grate bar 10' and the surface 19 of grate bar 10 is in contact with the surface 18'' of grate bar 10''. Since the air chutes 24 and the notches 20 and 21 on opposite sides of each grate bar are staggered with respect to each other, the mounting of a plurality of grate bars 10, 10' and 10'' side by side serves to locate the notches 20 and 21 of one grate bar, for example 10, opposite the air chute of the adjacent grate bars 10' and 10''. Referring to Figure 6 it will be observed that the air chute 24 of grate bar 10 is thus adjacent the notch 21'' of the grate bar 10'', and since the air chute 24 extends upward to a dimension A, which is greater than the lowermost edge of the air chute 21'', the air chute and notch thus overlap slightly, and air may accordingly move upwardly, as illustrated by the arrows 32 of Figure 4. The air is deflected outwardly by the outwardly slanted surface at the upper part of the air chute 24 and upon reaching the notch 21 which also converges upwardly, the air is distributed to a larger area of the grate than is represented merely by the cross section of the air chute 24. It will thus be observed that notches 24 and 24'' serve as metering orifices through which the volume of combustion air may be carefully controlled by suitable regulation of the draft on the grate. At the same time, the expanding notches 20 and 21 reduce the velocity of the air before it reaches the fuel bed and consequently diminishes fly-ash trouble.

Referring again to Figure 6, it will be observed that air chutes 24'' of grate bar 10'' lie opposite notches 21-21 of grate bar 10, and serve to deliver air to them in the same way as air chutes 24 deliver air to notches 21''. It may also be noted that there is no vertical passage through the grate assembly of a plurality of grate bars. See Figure 4.

The staggered relationship of the notches on opposite sides of the grate cause a definite swirling action of the air, as illustrated by the arrows 35 in Figure 3, thus causing the air to be distributed over a large portion of the solid fuel bed immediately in contact with the grate surface. It has been observed that with a grate surface of the design herein illustrated that there is a uniform distribution of air in a solid fuel bed, even where the fuel bed has a depth of as little as one inch, whereas grate surfaces of prior design showed definite points of intense burning with a fuel bed of corresponding depth. This proves the

more uniform distribution of combustion air in accordance with the design here presented.

In the grate design of the present invention the side of each grate lies in contact with the side of the adjacent grates, the air passage portion excepted. No space is therefore available through which sifting may occur, for the upward draft and bent configuration of the air passages (see Figure 4) serves to prevent downward movement of ash at these places. Sifting is therefore substantially eliminated.

As there are no interior areas in the grate design the entire grate surface may be cast by ordinary green sand molding and does not require any coring.

It is to be understood that the grate surface of the present invention is applicable to grate bars, chain grates, dumping or rocker grates and other forms of grates wherein air is delivered to the solid fuel bed. The form of support for the grate bar is adapted to the mechanical under-construction of the grate, and to the fuel and air feeding systems employed.

As many apparently widely different embodiments of this invention may be made without departing from the spirit and scope thereof, it is to be understood that I do not limit myself to the specific embodiments herein except as defined by the appended claims.

What I claim is:

1. A grate bar having a head portion composed of top and bottom surfaces and parallel flat side surfaces forming the extreme lateral surfaces of the bar, said surfaces being spaced apart a distance at least equal to the width dimension of the bar, the edges at the junction of the top and side surfaces being inwardly notched at evenly spaced intervals along each side, air-passage grooves in said sides, said grooves extending only part way up the side from the bottom of the side surfaces, each said air-passage groove being located in the side surface spaces between the notches, and a downwardly extending support below said head portion.

2. A grate bar having a head portion composed of top and bottom surfaces and parallel flat side surfaces forming the extreme lateral surfaces of the bar, said surfaces being spaced apart a distance equal to the width dimension of the bar, the edges at the junction of the top and side surfaces being inwardly notched at evenly spaced intervals along each side, the notches along one of the flat sides being staggered with respect to the notches along the opposite side, air-passage grooves in the sides, said grooves extending only part way up the side from the bottom of the side surfaces, each said air-passage groove being an indentation located in the side surface in the spaces between the notches, and a downwardly extending support below said head portion.

3. A grate bar having a head portion bounded by a top surface and parallel flat side surfaces, said side surfaces forming the extreme lateral surfaces of the bar, said surfaces being spaced apart a distance at least equal to the width dimension of the bar, the edges formed at the junction of the top and side surfaces being inwardly notched at regularly spaced intervals along each side, the notches along one side being staggered with respect to the notches on the other side, the surface of each said notch extending along an angularly disposed plane from near its bottom at the junction with the side surface in which it is located to near the middle of the top surface, said notches being of increased width from bot-

tom to top, and air passage grooves in the sides, said grooves being recessed into the side surfaces and reaching only part way up the side from the bottom of the side surfaces to a position above the bottom of the notch, each said air-passage groove being located in the side surface between the notches.

4. The apparatus of claim 3 further characterized in that the air-passage grooves have a width in the direction along the side of the grate bar, approximately equal to the bottom width of the notches.

5. A grate bar of the type set forth in claim 3 further characterized in that the junction of the top and side surfaces is slightly chamfered between notches.

6. A grate surface comprising a carrier support and a plurality of grate bars, the fire element of each grate bar being composed of a solid member having a flat top surface and parallel flat vertical side surfaces, said side surfaces each including flat continuous similarly shaped areas extending from one end of the grate bar to the other end, said areas each being a uniform distance from a vertical central plane through the bar, the opposite edges formed by the junction of said top and both side surfaces being notched at regular intervals, the width of notches and intervening spaces being approximately equal, the notches along one side being staggered so as to be opposite the spaces on the other side, air-chute recesses indented into the side walls and extending only part way up the sidewall from the lower edge of the side wall to a level above the lowermost part of the notches, said air-chute recesses being in the intervening spaces between the notches on each side, said grate bars being mounted side by side on the carrier support with the side surface of adjacent bars in contact so as to locate the air-chute recesses of one bar with the upper part of each air chute overlapping the lower part of the corresponding notches of adjacent grate bars, and with the flat continuous side area of one bar in contact with the similar area of the adjacent bar.

7. A grate bar wherein the fire element is composed of a solid member having a flat top surface and parallel flat vertical side surfaces, said side surfaces each including flat continuous similarly shaped areas extending from one end of the grate bar to the other end, said areas each being a uniform distance from a vertical central plane through the bar, the opposite edges formed by the junction of said top and both side surfaces being notched at regular intervals, the width of notches and intervening spaces being approximately equal, the notches along one side being staggered so as to be opposite the spaces on the other side, each said notch being a flat chamfered surface extending from a line of in-

tersection near but spaced above the lower edge of the side wall, said notches being of increasing width from bottom to top and terminated in line of intersection on the top surface, said line of intersection being between the centerline of the grate bar and the side surface, air-chute recesses indented into each of the side walls, each said recess extending only part way up the sidewall from the lower edge of the side wall and tapered out and terminated at a level above the line of intersection of the notch near the lower edge of the side wall, said air-chute recesses being in the intervening spaces between the notches on each side.

8. A grate bar of the type set forth in claim 7 further characterized in that the edges between the notches, formed by the junction of the top and side surfaces, is chamfered slightly.

9. A grate surface comprising a carrier support and a plurality of grate bars, the fire element of each grate bar being composed of a solid member having a flat top surface and parallel flat vertical side surfaces, said side surfaces each including flat continuous similarly shaped areas extending from one end of the grate bar to the other end, said areas each being a uniform distance from a vertical central plane through the bar, the opposite edges formed by the junction of said top and both side surfaces being notched at regular intervals, the width of notches and intervening spaces being approximately equal, the notches along one side being staggered so as to be opposite the spaces on the other side, each said notch being a flat chamfered surface extending from a line of intersection near, but spaced above, the lower edge of the side wall, said notches being of increasing width from bottom to top and terminated in line of intersection on the top surface, said line of intersection being between the center line of the grate bar and the side surface, air-chute recesses indented into the flat surface of each of the side walls, each said recess extending only part way up the sidewall from the lower edge of the side wall and upwardly, being then tapered out and terminated at a level above the line of intersection of the notch near the lower edge of the side wall, said air-chute recesses being in the intervening spaces between the notches on each side, said grate bars being mounted side by side on the carrier support with the side surfaces of adjacent bars in contact so as to locate the air-chute recesses at one bar with the upper part of each air chutelapping the lower part of the corresponding notches of adjacent grate bars, and with the flat continuous side area of one bar in contact with the similar area of the adjacent bar.

CHARLES V. CARROLL.
